COMBINED MAGAZINE RACK, SHELF, TOILET PAPER DISPENSER AND CIGARETTE ASH TRAY HOLDER

Eugene Gillard, El Cajon, Calif.

Application May 10, 1957, Serial No. 46,102

Term of patent 14 years

(Cl. D4—3)

Fig. 1

Fig. 2

Fig. 3

Figure 1 is a rear elevational view of a combined magazine rack, shelf, toilet paper dispenser and cigarette ash tray holder showing my new design;

Figure 2 is an perspective view thereof;

Figure 3 is an end elevational view thereof.

The undisclosed side of the article is the same in appearance as the side shown.

I claim:

The ornamental design for a combined magazine rack, shelf, toilet paper dispenser and cigarette ash tray holder, as shown and described.
